HENRY W. LANDOLT, OF BROOKLYN, NEW YORK.

WINDOW-SASH CONSTRUCTION.

1,108,914.

Specification of Letters Patent.

Patented Sept. 1, 1914.

Application filed March 6, 1913. Serial No. 752,447.

To all whom it may concern:

Be it known that I, HENRY W. LANDOLT, residing at Brooklyn, in the county of Kings and State of New York, have invented certain new and useful Improvements in Window-Sash Construction, of which the following is a specification.

This invention relates to window sash construction, and the particular object thereof is to provide a simple design therefor, whereby a sash of exceptional strength may be manufactured at comparatively small cost.

A further object is to provide a structure formed of parts so shaped and arranged as to be capable of easy assemblage, and to adapt said parts so that, when assembled, they will interlock with each other in substantially immovable relation, whereby each will lend its strength to the other in withstanding strains to which the sash may be subjected.

A further, and somewhat more detailed object, is to provide intersecting base or body members forming a lattice, and to provide separately formed molding pieces for positively locking the base members together.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings which are to be taken as a part of this specification, and in which I have shown a merely preferred form of embodiment of the invention: Figure 1 is a detail perspective view of a portion of a window sash constructed in accordance with the provisions of this invention, the marginal frame of said sash being illustrated in dotted lines, and parts of the lattice work of said sash being illustrated in fully assembled relation, and other parts being illustrated in process of assembling; and Fig. 2 is an enlarged detail sectional section being taken on the plane of line 2—2 of Fig. 1, looking in the direction of the arrow.

Referring to the drawings for a detailed description of the parts and their method of assembling, the reference numeral 1 indi-

cates a plurality of vertically disposed lattice pieces, which will be hereinafter referred to as the vertical base members. They extend from top to bottom of the marginal frame 2 of the sash, being capable of attachment to said marginal frame in any preferred manner. In a sash structure there may be as many of the pieces 1 as may be desired, according to the width of the sash or of the size desired for the glass sections between said pieces.

The numeral 3 indicates a plurality of lattice pieces extending transversely of the base members 1 preferably from side to side of the sash frame, and being capable of attachment to said side pieces in any suitable manner. These will be hereinafter referred to as the horizontal base members, and may also be in any number according to the height of the sash and according to the height of the glass section to be disposed between them. The base members 1 and 3 therefore are adapted to define a plurality of rectangular areas within the marginal frame 2 of the sash, each of said areas to be closed or filled with rectangular pieces of glass 4, as will be understood.

The base members 1 and 3 are preferably of substantially identical cross section, each comprising a web portion 5 and a head portion 6 extending longitudinally at one edge of the web and forming therewith a T-bar. The opposite longitudinal edges 7 of the head portion 6 of each of the pieces 1 and 3 are inclined relatively to each other, as best seen in Fig. 2, from the outer surface of the head inwardly toward the web 5 for a purpose presently to be described. These base members intersect each other, and at the several points of intersection they are provided with cut out portions or slots 8 and 9 respectively, so that the pieces may be nested together in a well-known manner. It is immaterial which of the sets of base members are provided with the slots extending through the head portion thereof, but for the purpose of illustration the members 3, extending from side to side of the sash are provided with such slots. With this understanding several of the members 3 may have their slots 9 engaged with one only of the members 1, the single member 1 serving to hold the several members 3 in spaced relation, this being done before any of the members are inserted within the frame 2.

A molding piece 10, having a dove-tailed

slot 11 extending longitudinally in its under surface, is attached to the base member 1 by telescoping the head portion 6 of the member 1 within the dove-tailed groove 11 of the molding, the opposite inclined edges 7 of the head serving to positively retain the molding against detachment laterally from the head. This molding piece 10 is of continuous cross section being preferably entirely devoid of any notches or cut-away parts whatever so as to attain maximum strength.

In the case of the first base member 1 to be assembled, the molding 10 may be attached to the base before the said base is assembled with the horizontal base members, but it may be here noted that in assembling subsequent base members 1, this is not the case, as will be presently apparent.

20 Molding pieces 12, similar to the piece 10, except as to length, are applied to the head portions 6 of base members 3, the dove-tailed grooves of said molding pieces 12 engaging with the inclined sides of the head portions 6 of base members in the same manner as does the molding 10 with the head portion of the base member 1, above referred to.

The molding pieces 12 are cut to a length 30 commensurate with the space desired between the vertical members of the lattice, that is, with the slots 9 formed in the base members 3, and the opposite ends of the molding pieces 12 are coped away so as to 35 form relatively overhanging parts 13 shaped to fit closely about shoulder portions 14 formed on the relatively outer surface of the molding piece 10 as best seen in Fig. 2. The molding pieces 12 are telescoped longitudinally over the head portion 6 of the 40 base members 3 from opposite directions until the ends 13 thereof engage closely over the shoulder portions 14 of the molding 10.

With the structure thus far assembled, a 45 second vertical base member 1 may be inserted, or nested, within the next row of slots 9 of the base members 3. Such a base member 1 is illustrated at the right of Fig. 1 in position to be engaged in the slots 9 of 50 the base pieces 3 after the lower molding piece 12 has been moved to the left to uncover the slot 9 in the lower base member 3. In this instance the molding piece 10 for the base member 1 may not have been previously attached to said member, but must be telescoped longitudinally over the head portion thereof after the member 1 is placed. In this way the projecting shoulder portions 14 of the molding 10 of said member 55 will be inserted beneath the relatively projecting ends 13 of the molding pieces 12 already assembled and serve thus to positively and rigidly lock the base member 1 to each of the base members 3 of the structure. The lock is further strengthened by

the placing of other molding pieces 12 at the opposite, or right hand, side of the molding 10 just placed.

Each subsequent vertical base member 1 must be attached in the same manner as that just described, and molding sections 12 applied to the base members 3 before the next succeeding vertical base member 1 may be assembled.

The moldings 10 and 12 are easily applied 75 by telescoping over the heads of the base members, and are as easily detached therefrom in the same manner, no tools being required for either operation.

When the full lattice portion of the sash 80 is thus assembled, it is inserted within the marginal frame 2 which may have been already constructed, or which may be built about the lattice and attached thereto in any desired manner, the details of which attachment are not important to the features 85 of this invention, the only essential of the frame being to lend added strength to the lattice and provide shoulder portions as at 15 for preventing longitudinal detachment 90 of the outer molding pieces 12 and also of the molding pieces 10.

It may be here noted that, in the completed lattice, each of the molding pieces 12 is positively held against longitudinal movement by the engagement of its opposite ends with the sides of the moldings 10 so 95 that both the moldings 10, and their base members 1, are held by each molding piece 12, and it is practically impossible to disassemble the lattice except by telescoping the moldings 10 longitudinally off of the base members 1. This may however be done whenever desired since the moldings are all readily detachable.

The head portion 6 of the cross pieces 3 is cut out for a short distance at opposite sides of the slots 9 as at 18 for accommodating the over-hanging portions of the moldings 10, forming a sort of groove through 110 which the moldings 10 may slide. The over-hanging portions 13 of the moldings 12 also provide a sort of groove through which the molding 10 may slide.

The web portions 5 of the base members 1 115 and 3 define the rectangular areas within which the glass sections 4 are confined, and the under surface portions 16 of the moldings 10 and 12 provide a shoulder extending around said areas against which the inner 120 surface of the glass sections rest. Retaining members 17 for the glass sections are attached to the web portions 5 and engage the outer surface of the glass to hold it against detachment. These retaining pieces may be 125 formed of any material, but preferably comprise angle sections arranged with one leg resting against the web 4 and with the other leg resting against the surface of the glass, the first mentioned leg being connected to 130

the web by a screw or other device 19 which may obviously extend through the web and serve as the retaining means for a similar glass holding element at the opposite side of the web, or not, as desired.

The continuous uninterrupted formation of the molding pieces 10, it will be noted, add very materially to the strength of the vertical base members 1. These base members being formed with notches 8 in their web portions spaced from the head thereof are considerably weakened, and the continuous integral formation of the molding attached to the head will in a great measure 10 compensate for the loss occasioned by the presence of the slots 8. The moldings 10, by their intimate engagement with the molding pieces 12, will transmit their strength through said molding pieces 12 to the base members 3. The notches in the base members 3, being formed through the head portion thereof, leaves a portion of the web only to resist lateral strains, but the interlocking relation of the ends of the molding 20 pieces 12 with the moldings 10 will fully compensate for the loss sustained in the cutting away of the head portion.

Forces tending to bow out the window from the inside, that is, from the side to 30 which the moldings are attached, will be resisted by the vertical pieces 1, which, with the continuous molding pieces 10 fixed thereto, will effectually resist such strains, the molding being relatively under compression 35 longitudinally, and the outer longitudinal edge of the web portion 4 being relatively under tension. The strength of the structure in resisting forces from within is materially increased by the base members 3 where the moldings 12 will also be relatively 40 under compression, and the outer longitudinal edges of the web portions of the base member being relatively under tension. The sides of the apertures 9 will grip 45 against the opposite side surfaces of the web 5 of the base members 1, and this in effect, will complete the web of the members 3 to their full cross section. The ends of the molding pieces 12 will wedge against the 50 opposite sides of the moldings 10 and this also will, in effect, complete the moldings 12.

Forces tending to bow the structure inwardly will be opposed principally by the vertical base members 1, which, it will be 55 noted, are fully capable of withstanding a very considerable pressure from without for the reason that they will present to such forces substantially their full cross section unimpaired continuously of their length, the sides of the notches 8 gripping against the opposite surfaces of the webs 5 of the base members 3. The connecting portions at the notches 9 of the base members 3 will also serve to resist forces from without. 60 The interlocking engagement of all of the

parts will, of course, serve to resist forces both from within and from without.

It is thus seen that I have provided a structure of simple parts, easily and cheaply manufactured, and capable of being assembled into an exceptionally rigid lattice by simple operations of assembling. The cost of the structure is considerably reduced without sacrificing strength, and the parts may be readily disassembled whenever de- 70 sired. 75

While I have illustrated the moldings 10 and 12, in each instance to comprise a solid structure, such as wood it is apparent that these moldings may be readily formed of 80 sheet metal, if desired.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claims is intended to cover all of the generic and specific features of the invention herein described and all statements of the scope of the invention, which as a matter of 95 language, might be said to fall therebetween.

Having thus described my invention what I claim as new and desire to secure by Letters Patent, is:

1. A window sash structure comprising 100 intersecting base members, and molding pieces detachably carried by said base members and serving to lock said base members together.

2. A window sash structure comprising 105 intersecting base members notched together, and separately formed molding pieces secured to said base members interlocking with each other to retain said base members locked together.

3. A window sash structure comprising 110 intersecting base members notched together, and means locking said base members notched together at the points of intersection comprising separately formed molding 115 pieces carried by said base members respectively, said molding pieces being readily adjustable into and out of locking position upon said base members.

4. A window sash structure comprising 120 intersecting base members notched together, and means for retaining said base members in locked relation, comprising separately formed molding pieces detachably interlocked therewith and with each other.

5. A window sash structure comprising a 125 plurality of intersecting base members, each comprising a T-section, and separately formed members extending longitudinally along the length of the head portions of

130

said T-sections and interlocking with each other to lock said T-sections together.

6. A window sash structure comprising a plurality of base members, each comprising a T-section, and separately formed means attached to the head portions of said T-sections, interlocking with each other to lock said T-sections together.

7. A window sash structure comprising a plurality of intersecting base members, each comprising a T-section, and separately formed ornamental molding pieces attached to the head portion of said T-sections interlocking with each other to lock said T-sections together.

8. A window sash structure comprising a plurality of intersecting base members, and separately formed ornamental molding pieces connected to said base members the molding piece connected to one of said base members being movable longitudinally along said base member to engage the molding piece connected to the other of said base members to lock said base members together.

9. A window sash structure comprising intersecting base members, a molding piece carried by one of said base members, a molding piece carried by the other of said base members by having dove-tailed grooves engaging coöperative portions of said last base member, and the molding piece connected to said second base member being movable longitudinally along said base member by means of said dove-tailed grooves to engage the molding piece connected to the other of said base members to lock said base members together.

10. A window sash structure comprising a plurality of intersecting lattice members, and means attached to one of said lattice members movable longitudinally thereof for engaging a portion of another of said lattice members to lock said lattice members together.

11. A window sash structure comprising a plurality of intersecting base members, and separately formed means attached to said base members respectively forming shoulders against which the glass portion of the window sash may engage, and the separately formed means attached to one of said intersecting base members extending into interlocking relation with the separately formed means attached to the other of the intersecting base members to lock said base members together.

12. A window sash structure comprising a plurality of intersecting base members, each of said base members comprising a T-section and said T-sections being notched together at their points of intersection, means attached to one of said T-sections to form under-cut grooves at opposite sides of the notch therein, and means attached to the other of the T-sections extending through

said grooves whereby to lock said T-sections together.

13. A window sash structure, comprising a plurality of intersecting base members, one of said base members having a notch formed therein to receive a portion of another base member, means carried by the first mentioned base member forming an under-cut groove adjacent said notch, and means carried by the other of said base members extending through said groove adapted to prevent detachment of said second base member from said first member.

14. A window sash structure, comprising a plurality of intersecting base members, one of said base members having a notch formed therein to receive a portion of another base member, means carried by the first mentioned base member forming an under-cut groove adjacent said notch, and means carried by the other of said members telescopically adjustable longitudinally thereof, adapted to engage in said groove to prevent detachment of said first base member from said second base member.

15. A window sash structure formed of a plurality of intersecting base members, each comprising a member having a head portion and a web portion extending longitudinally thereof, means detachably engaging the head portions adapted to be locked together for locking said base members together and forming shoulders against which one surface of the glass portion of the sash may engage, and means detachably engaging the web portions of said base members for retaining the glass portions of the sash against displacement.

16. A window sash structure comprising a plurality of intersecting lattice members, and means attached to one of said lattice members movable longitudinally thereof for engaging a portion of another of said lattice members to lock said lattice members together and means carried by a third lattice member for preventing retrogression of said movable means.

17. In a window sash structure, a pair of spaced lattice members, a lattice member extending between said pair of lattice members, and a separately formed longitudinally detachable member carried by said second mentioned lattice member engaging said pair of lattice members to lock all of said lattice members together, and being held by said pair of lattice members against longitudinal movement.

18. A sash structure comprising intersecting metallic base members, and wood molding pieces connected to said metallic base members, said wood molding pieces engaging with each other to lock said metallic base members together.

19. A sash structure comprising intersecting base members, a molding piece carried

by one of said base members, the other of the base members being formed with a cut away portion to receive a part of said molding piece, and a part carried by the second base member over lapping that portion of the molding piece which extends into the cut away portion to retain said base members locked together.

20. A sash structure comprising a plurality of intersecting base members, one of said base members having a notch formed therein to receive a portion of another base member, a molding piece carried by one of said base members having a part extending into the notch of the other base member, and a molding piece carried by the second base member over lapping that portion of the first molding piece which extends into the notch of the second base member, to retain said base members locked together.

21. A sash structure comprising a plurality of base members extending longitudinally in planes intersecting, and molding members connected to said base members engaging with each other to retain said base members in fixed relation to each other.

22. A sash structure comprising a plurality of base members extending longitudinally in planes intersecting, and molding

members connected to said base members, 30 the base members and molding members which extend in one direction being longitudinally adjustable relatively to each other to dispose said members for engaging relatively opposite surfaces of one of the members which extend in the other direction so as to retain all of said members in fixed relation to each other.

23. A sash structure comprising a plurality of base members extending longitudinally in planes intersecting, and molding members connected to said base members, the base members and molding members which extend in one direction being telescopically connected so as to be longitudinally adjustable relatively to each other to dispose said members for engaging relatively opposite surfaces of one of the members which extend in the other direction so as to retain all of said members in fixed 50 relation to each other.

In testimony whereof, I affix my signature in the presence of two witnesses.
